FRED B. MANLEY, OF PATERSON, NEW JERSEY, ASSIGNOR TO TEXTILES DEVELOPMENT CORPORATION, OF NEW YORK, N. Y., A CORPORATION OF DELAWARE.

METHOD OF AND APPARATUS FOR WEAVING.

Application filed January 30, 1923. Serial No. 615,813.

In the production of certain fabrics, it is desired to twist adjacent wrap strands around each other between successive picks of filling. It is one of the objects of my present invention to provide apparatus by which such twisting of warp strands may be readily and efficiently carried out, and particularly apparatus by which such strands may be twisted around each other 10 as many times as desired. Other objects of my invention will appear from the following description and the appended drawings, in which:

Fig. 1 is a front elevation of an illustrative embodiment of a portion of my apparatus for producing twists in adjacent warp strands

Fig. 2 is a section on the line 2—2 of Fig. 1, on a somewhat enlarged scale, and showing the warp strands in position

Fig. 3 is a front elevation of a pair of heddles used in the illustrative form of my invention

Fig. 4 is a side view of Fig. 3

Fig. 5 is a side view of a loom, more or less diagrammatically represented, and in which the usual parts of the loom not concerned with my present invention are omitted, and

Fig. 6 is similar to Fig. 5, with some of the parts in different positions.

Fig. 7 illustrates the attachment of the heddles to the heddle bars.

Like reference characters indicate like parts in the several views.

In the drawings I have illustrated my invention in connection with a fabric in which the twisting of the warp strands occurs only at predetermined times in the weaving operation, and not one in which the warp is twisted between each pick of filling, as may be done in some cases. In producing the kind of fabric illustrated, I provide the usual harness and, in the illustrative form, such a harness is controlled by the usual dobby to form the shed, and the desired pattern. The warp beams 10 and 35, the dobby 11, the harness strap 12, the reed 13 and the breast beam 14 are of the usual type, the warp being carried over the usual guides through the reed 13 into the fell of the cloth passing over the breast beam 14. It will be understood that the

loom has the usual construction to operate these parts in the known manner.

The heddles 15 are preferably of the form shown best in Figs. 3 and 4, being made, in the illustrative form, of thin sheet metal having their ends twisted so that they may be suspended in the harness and each heddle being provided at its central portion with an opening 16 extending to the side of the heddle, which opening is of considerable length vertically, and preferably a recess 17 above the opening 16 and a recess 18 below the opening 16 are provided, the recesses 17 and 18 being of the width of the usual diameter of the heddle opening for the size yarn used in the fabric being woven.

In weaving the fabric between the portions having twisted warp strands, the heddles 15 are controlled by the dobby and harness in the usual manner to form the shed for successive picks, each warp strand W, W' being raised and lowered in the usual manner by one of the heddles 15, each strand passing alternately into the recesses 17 and 18 as such strand is to be raised or lowered. Heddle bars 37 pass through the top and bottom slots 36 of the heddles, and the heddles are held thereon in such a position that they can be raised or lowered. On each side of this slot, both top and bottom, supporting the heddle is a clip 38.

Adjacent the heddles and at the rear thereof, I place my novel warp strand twisting arrangement, which, in the illustrative form, is made up of a plurality of twisting members 19. These members are each in the form of a quill having a bearing 20 on the opposite ends thereof and having gear teeth 21, and are connected, in turn, to a bar 23 extending across the loom frames, indicated at 24, 24 in Fig. 1.

Each of the twisting members 19 is provided with a pair of strand guideways 25 extending longitudinally through the quill and, in the form illustrated, these guideways are located on opposite sides of the axes of the twisting members and at the same distance therefrom. It will be understood that, if desired, the twisting members may have more than two guideways, according to the kind of twist desired to be given to the warp strands.

The twisting members 19 are turned on

their axes, in the illustrative form, by means of a rack 26 resting on the teeth 21 and engaging therewith, and held in place by rollers 28 carried in bearings 27, 27. In the illustrative embodiment, the rack 26 is reciprocated by a lever 29 at each end having a fork engaging with a pin 30 on the end of the rack 26, the lever 29 being pivoted at 31 on the loom frame and having an arm 32 provided with a pull spring 33 and connected through a cable 34 with the dobby 11, the dobby being arranged to operate the rack 26 in accordance with the number of twists to be given to the warp strands and at as many times to each repeat as may be desired.

The warp strands W, W' are carried from the warp beam 10 through the twisting members 19 and the heddles 15 into the fell of the cloth, and in the following description, the operation of a pair of adjacent strands will be described, it being understood that as many of such warp strands as are desired will be similarly twisted. During the weaving of the portion of the pattern in which the warp strands are not twisted, the shed will be formed as shown best in Fig. 5, the twisting member 19 at that time preferably being turned, so that the guideways 25 are in the same horizontal plane. Obviously when the parts are in this position, the warp strands will pass through the twisting members 19 without being affected thereby, and the strands may be lifted and lowered to form the shed in the usual manner.

When it is desired to twist a pair of adjacent warp strands, the harness is operated so as to move the heddles 15 into the position shown in Figs. 3 and 6, with the openings 16 opposite each other. Then the rack 26 is moved to cause the members 19 to turn as many times as it is desired to produce twists in the strands. By having the openings 16, 16 opposite each other, the strands W, W' are temporarily freed from the heddles so that they may turn around each other to produce the twists, as indicated at T. After the twists are given to warp strands, the shed is again opened and a pick of the filling inserted and beaten up in the usual manner, so that the twists in the warp are locked in position. When the twist T is produced in the fell of the cloth, it will be obvious that a corresponding reverse twist will be produced at T' on the opposite side of the harness. The twist T' may be allowed to remain while the warps are shedded in the ordinary manner and picks of filling are inserted, or it may be removed immediately after the beating up of the pick of filling which has just locked the twist T in position. The twist T' may be removed by bringing the heddles to the position shown in Figs. 3 and 6 and then actuating

the rack in the opposite direction back to its original position. This operation will introduce a new twist T in a direction opposite to the direction of the preceding twist T, the warps being straight in the rear of the heddles. A pick of filling may then be inserted and beaten up as before to lock the new twist T in position. Picks of filling may then be inserted in the ordinary manner, all the warps now being straight, or the twisting mechanism may be actuated as before.

It will be obvious that with the arrangement shown in Figs. 1 and 2, there is substantially no limit to the number of times the warp strand may be twisted around adjacent warp strands, the number of twists being determined entirely by the number of turns of the twisting members 19, which, in turn, will be determined by the motion of the rack 26. Moreover, by passing the warp strands through guideways extending substantially in the same direction as the warp strands, no sharp bends are produced in the warp strands, the spring slackener 39 taking care of the extra length required to open the heddles, and there is, therefore, substantially no tendency to break such strands.

While, in the illustrative embodiment I have shown all of the warp as passing through twisting members, it will be understood that if the fabric is to have twisted warp strands only at intervals across the fabric, the twist may be omitted at the places where the warp is not to be twisted, by the removal of the twisting members 19. In this event, the warps to be twisted may be taken off one warp beam, and those not twisted, off another warp beam, as the latter warps will be shorter than the twisted warps.

I claim:

1. In a loom, means for twisting a pair of adjacent warp strands while the loom is in operation, comprising a twisting member having a plurality of guideways extending therethrough lengthwise of the warp strands, and means to rotate said twisting member, combined with harness mechanism for shedding the warps of the twisted pair relative to one another, said harness mechanism including a pair of heddles so interrelated that each heddle may raise or lower either thread of the pair, the thread being transferred from one heddle to the other heddle during the rotary movement of the twisting member, each heddle acting on the particular thread placed in it by the twisting member through which it passes.

2. In a loom, means for twisting a pair of adjacent warp strands while the loom is in operation, comprising a twisting member having a plurality of guideways extending therethrough lengthwise of the warp strands, and means to rotate said twisting member through a plurality of rotations,

combined with harness mechanism for shedding the warps of the twisted pair relative to one another, said harness mechanism including a pair of heddles so interrelated that each heddle may raise or lower either thread of the pair, the thread being transferred from one heddle to the other heddle during the rotary movement of the twisting member, each heddle acting on the particular thread placed in it by the twisting member through which it passes.

3. In a loom, means for twisting a pair of adjacent warp strands while the loom is in operation, comprising a twisting member having a plurality of guideways extending therethrough lengthwise of the warp strands, said member being mounted for rotation on an axis parallel to the warp strands, and means to rotate said twisting member, combined with harness mechanism for shedding the warps of the twisted pair relative to one another, said harness mechanism including a pair of heddles so interrelated that each heddle may raise or lower either thread of the pair, the thread being transferred from one heddle to the other heddle during the rotary movement of the twisting member, each heddle acting on the particular thread placed in it by the twisting member through which it passes.

4. In a loom, means for twisting a pair of adjacent warp strands while the loom is in operation, comprising a twisting member having a plurality of guideways extending therethrough lengthwise of the warp strands, said member being mounted for rotation on an axis parallel to the warp strands and located between said guideways, and means to rotate said twisting member, combined with harness mechanism for shedding the warps of the twisted pair relative to one another, said harness mechanism including a pair of heddles so interrelated that each heddle may raise or lower either thread of the pair, the thread being transferred from one heddle to the other heddle during the rotary movement of the twisting member, each heddle acting on the particular thread placed in it by the twisting member through which it passes.

5. In a loom, means for twisting a pair of adjacent warp strands while the loom is in operation, comprising a twisting member having a plurality of guideways extending therethrough lengthwise of the warp strands, said member being mounted for rotation on an axis parallel to the warp strands and located between said guideways, and means to rotate said twisting member through a plurality of rotations, combined with harness mechanism for shedding the warps of the twisted pair relative to one another, said harness mechanism including a pair of heddles so interrelated that each heddle may raise or lower either thread of the pair, the

thread being transferred from one heddle to the other heddle during the rotary movement of the twisting member, each heddle acting on the particular thread placed in it by the twisting member through which it passes.

6. In a loom, means for twisting a pair of adjacent warp strands while the loom is in operation, comprising a twisting member having a plurality of guideways extending therethrough lengthwise of the warp strands, said member being mounted for rotation on an axis parallel to the warp strands, a gear on said member and a rack engaging said gear to rotate said member, combined with harness mechanism for shedding the warps of the twisted pair relative to one another, said harness mechanism including a pair of heddles so interrelated that each heddle may raise or lower either thread of the pair, the thread being transferred from one heddle to the other heddle during the rotary movement of the twisting member, each heddle acting on the particular thread placed in it by the twisting member through which it passes.

7. In a loom, a support extending across the loom, a plurality of twisting members mounted in said support and each arranged to be rotated on an axis parallel with the warp strands, a plurality of guideways extending through each of said members in the general direction of the axis thereof, means to rotate all of said members simultaneously on their respective axes, and harness mechanism for shedding the warps of the twisted pairs relative to one another, said harness mechanisms each including a pair of heddles so interrelated that each heddle may raise or lower either thread of the corresponding pair, the thread being transferred from one heddle to the other during the rotary movement of the corresponding twisting member, each heddle acting on the particular thread placed in it by the twisting member through which it passes.

8. In a loom, a support extending across the loom, a plurality of twisting members mounted in said support and each arranged to be rotated on an axis parallel with the warp strands, a plurality of guideways extending through each of said members in the general direction of the axis thereof, and means to rotate all of said members simultaneously on their respective axes, said means comprising a gear on each member and a reciprocating rack engaging all of said gears, said harness mechanisms each including a pair of heddles so interrelated that each heddle may raise or lower either thread of the corresponding pair, the thread being transferred from one heddle to the other during the rotary movement of the corresponding twisting member, each heddle acting on the particular thread placed in it by the twisting member through which it passes.

9. A loom comprising a harness having a pair of heddles for adjacent warp strands, each heddle having an opening in the side thereof adjacent the other heddle of the pair, a twisting member for the warp strands engaged by said heddles, said twisting member being arranged to twist such warp strands above each other, means to operate said twisting member, and means to operate the harness to bring said openings side by side when the twisting member is operated.
10. A loom comprising a harness having a pair of heddles for adjacent warp strands, each heddle having an opening in the side thereof adjacent the other heddle of the pair and a recess above and a recess below said opening, a twisting member for the warp strands engaged by said heddles said twisting member being arranged to twist such warp strands about each other, means to operate said twisting member, and means to operate said harness to form a shed between the warp strands and to bring the warp strands to substantially the same level with said openings side by side when the twisting member is operated.
11. A heddle having an opening in its side substantially longer vertically than the diameter of the strands to be controlled by the heddle, said heddle having a recess above and a recess below said opening and extending into said opening.
12. In a loom, means for twisting a pair of adjacent warp strands while the loom is in operation, comprising a twisting member having a plurality of guideways extending therethrough lengthwise of the warp strands, and means to rotate said twisting member, combined with a vertically moving harness mechanism for shedding the warps of the twisted pair, said harness mechanism including a pair of heddles so interrelated that each heddle may raise or lower either thread of the pair, the thread being transferred from one heddle to the other during the rotary movement of the twisting member, each heddle acting on the particular thread placed in it by the twisting member through which it passes.
13. In a loom, means for twisting a pair of adjacent warp strands while the loom is in operation, comprising a twisting member having a plurality of guideways extending therethrough lengthwise of the warp strands, said member being mounted for rotation on an axis parallel to the warp strands and means to rotate said twisting member, combined with a vertically moving harness mechanism for shedding the warps of the twisted pair, said harness mechanism including a pair of heddles so interrelated that each heddle may raise or lower either thread of the pair, the thread being transferred from one heddle to the other heddle during the rotary movement of the twisting member, each heddle acting on the particular thread placed in it by the twisting member through which it passes.
14. In a loom, means for twisting a plurality of pairs of adjacent warp threads while the loom is in operation, comprising a plurality of twisting members each having a pair of guideways extending therethrough lengthwise of the warp threads, means for turning the adjacent twisting members on their respective axes to thereby introduce twists in the adjacent pairs of warp threads, combined with harness mechanism for shedding the warps of each of the twisted pairs, and a shuttle for inserting a pick of filling into the shedded warps, said harness mechanisms each including a pair of heddles so interrelated that each heddle may raise or lower either thread of the corresponding pair, the thread being transferred from one heddle to the other during the rotary movement of the corresponding twisting member, each heddle acting on the particular thread placed in it by the twisting member through which it passes.

Signed at New York city, in the county of New York and State of New York, this 17th day of January, 1923.

FRED B. MANLEY. [L. S.]
